CLAIM

The ornamental design for a hockey stick-shaped drinking vessel, as shown and described.

DESCRIPTION

FIG. 1 is a front perspective view of a hockey stick-shaped drinking vessel showing our new design;

FIG. 2 is a right side view thereof;

FIG. 3 is a left side view thereof;

FIG. 4 is a rear view thereof;

FIG. 5 is a front thereof;

FIG. 6 is a top view thereof;

FIG. 7 is a bottom view thereof; and,

FIG. 8 is a cross section view taken along 8-8 of FIG. 6. The dash-dash broken lines show portions of the hockey stick-shaped drinking vessel that form no part of the claimed design. The dash-dot broken lines immediately adjacent to the shaded areas define the bounds of the claimed design and form no part of the claimed design.
